UNITED STATES PATENT OFFICE.

WYNNE JOHNSON, OF WASHINGTON, DISTRICT OF COLUMBIA.

ARTICLE AND PROCESS FOR PRODUCING ILLUSTRATIONS.

Application filed May 9, 1925. Serial No. 29,241.

This invention relates to the production of commercial illustrations, and presents a novel method, whereby printed stock designs may be combined with original drawings to produce finished illustrations, thus effecting a great saving of time and labor. It is particularly adapted for that form of commercial advertising illustration extensively used by retail stores for newspaper advertising.

10 Retail stores not sufficiently important to employ their own corps of artists usually subscribe to what is known in the trade as a "service." This "service" consists usually of a booklet containing prints of shoes, fashions, furniture, etc., with appropriate backgrounds and decorations. The trouble hitherto experienced in using these "services" is that the prints furnished may not exactly depict the article the store has for sale.

20 The principal object of this invention is to provide a method and articles for producing illustrations, whereby the stock cuts of such "services" as described may, with slight additions or changes thereto by an artist, not necessarily highly skilled, be made into an exact representation of the article which the store has for sale. This is of great advantage in advertising as it enables the prospective purchaser to get an exact and pleasant impression of the article for sale.

30 A still further object is to provide a process enabling the advertiser to select from his "service" an elaborate background, figure, decoration, etc., upon which an exact picture of the article for sale may be drawn, thus effecting great saving of time and money.

Other objects and advantages will become apparent during the course of the following specification and claims; as for instance, this method may be used to advantage in the making of animated cartoons in motion pictures.

Referring now to the drawings illustrative of certain applications of my invention:

Figure 1 represents a stock fashion figure such as is customarily drawn by an artist before applying the costume;

50 Figure 2 represents the same stock figure after the garment has been added by the artist in accordance with my process;

Figure 3 represents the third stage or completed illustration as it would appear in an advertisement or the like.

In the present instance, I have shown my

process as carried out in making a fashion figure, but it is to be understood that this is to be taken only as an example of one of many applications.

60 The numeral 4 indicates a stock design for a fashion figure which is printed in ink visible to the eye, but actinic or not visible to a camera as used during the ordinary photographic method of making zinc cuts.

65 The figure is represented in dotted lines to distinguish from lines visible to both eye and camera which are shown in the other two views as full lines.

70 There are two principal ways of producing a design of the character described, and indicated by the numeral 4. One is to print said design in a light blue ink, it being well-known that this color does not photograph readily. The other and preferable method 75 of producing the design is by printing the same in one of the many varieties of sympathetic inks. The ink must be of such color or so light in tone that it will not photograph, and capable of development by means 80 of a reagent, such as mineral acid, water, or the like to a color or tone that will photograph. I have found that such an ink may be prepared with the dye commercially 85 known as Congo Red, this dye having the property of changing from a light blue to a bright pink upon reacting with an alkali, and may be changed back to its original color by the application of a weak mineral acid. However, the nature of the ink used 90 for producing the stock design constitutes no part of my invention, and any of the inks described in the following list of United States patents might be used, depending 95 upon the particular character of the design desired: Charles F. Morse, 1,423,246; Otto Meyer, 456,047; Ernst Kretschman, 664,956; J. A. Inhof, 1,528,925, and others.

Having obtained the stock design, in 100 the present instance in sympathetic ink, the next step is to add the desired costume, as indicated by the numeral 5 in Figure 2. The costume 5 is sketched in black ink, wash or any desired medium, directly upon the design 4, as clearly shown in Figure 2.

105 The next step is to develop, so that they will be visible to the camera, the parts of the design not covered by the costume. Thus they may be photographed together, producing a completed illustration, as indicated in Figure 3, which shows the illustration 110 as it would appear after being submitted to

the photographic zinc etching process and printed for advertising purposes or the like.

In the first stated method of producing the stock design, wherein it is printed in ordinary light blue ink, the third step of the operation is of course omitted, and all parts of the design which it is desired to show in the completed illustration must be traced by hand in black ink. Those left in the original blue color will not photograph, thus the same result is obtained, but the method is slower and requires a more expert artist for the additional work upon the stock design.

15 In stock designs of a certain class, that is, in which very little of the stock design is intended to be covered by the subsequent sketch, I have found it advantageous to print the whole design in sympathetic ink 20 of a color or hue that will photograph, depending upon the reagent only to, photographically speaking, obliterate by changing, the portion covered by the sketch or not desired to reproduce, thus reversing the 25 operation described in the third step.

My method of producing illustrations is practicable, using as the stock design, line cuts, line cuts with Ben Day effects, half-tones, or any of the ordinary methods of 30 reproduction in use. It is thus evident that any desired medium or technique may be used in the drawing, from which the stock cut is made, and likewise in the subsequent drawing made upon the print of the stock 35 cut.

“Visible to the camera” is used to indicate color or tone which will be visible by contrast when photographed.

“Invisible to the camera” is used to indicate color or tone which will not show by contrast when photographed.

What I claim, is:

1. An article of manufacture for use in

the production of commercial illustrations, comprising a stock picture adapted for elaboration by drawing thereupon, said picture being printed in an ink visible to the eye, but invisible to the camera but capable of being rendered visible to the camera by suitable treatment.

2. The process consisting of producing a design visible to the eye but not visible to the camera, causing said design and further elaboration thereupon to be visible to the camera.

3. The process of producing a commercial illustration, consisting in printing a stock design in a medium visible to the eye but invisible to the camera, elaborating upon said design by drawing thereupon in a medium visible to both eye and camera, and causing selected portions of said stock design to become visible to the camera for photographing.

4. The process of producing commercial ornamentation consisting of printing a design in a sympathetic ink, elaborating on said design, and then so treating said first named design to change its actinic quality.

5. A step in the process of making illustrations from a skeleton base common to a plurality of illustrations, consisting of changing the actinic quality of a portion of the base.

6. An article of manufacture for use in the production of commercial illustrations, comprising a stock picture adapted for elaboration by drawing thereon, said picture being printed in an ink of one actinic value and capable of having the actinic value of certain portions thereof changed by suitable treatment.

In testimony whereof, I affix my signature.

WYNNE JOHNSON.
